US00D909405S

(12) **United States Design Patent** (10) **Patent No.:** **US D909,405 S**
Kim et al. (45) **Date of Patent:** ** ***Feb. 2, 2021**

(54) **DISPLAY SCREEN OR PORTION THEREOF
WITH GRAPHICAL USER INTERFACE**

G06F 3/0485; G06F 3/04855; G06F 3/0486; G06F 3/0488; G06F 3/04886; G06F 9/4443

(71) **Applicant:** **Samsung Electronics Co., Ltd.**, Suwon-si (KR)

See application file for complete search history.

(72) **Inventors:** **Daewon Kim**, Seoul (KR); **Hyun Yeul Lee**, Seoul (KR); **Insheik Martin Jung**, Seattle, WA (US); **Hyosang Bang**, Seoul (KR); **Youngseong Kim**, Seoul (KR); **Jaewon Park**, Seoul (KR); **Jiyoung Han**, Seoul (KR)

(73) **Assignee:** **SAMSUNG ELECTRONICS CO., LTD.**, Suwon-si (KR)

(*) **Notice:** This patent is subject to a terminal disclaimer.

(**) **Term:** **15 Years**

(21) **Appl. No.:** **29/653,189**

(22) **Filed:** **Jun. 13, 2018**

CLAIM

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outermost broken lines illustrate a display screen or portion thereof and form no part of the claimed design. The remaining broken lines in the drawings illustrate portions of the graphical user interface that form no part of the claimed design.

1 Claim, 2 Drawing Sheets

FIG. 1

FIG. 2
